NECKTIE HOLDER

Joseph J. Nugent, Pleasantville, N. Y.

Application August 19, 1938, Serial No. 225,821

3 Claims. (Cl. 2—153)

This invention relates to neck tie holders and has for an object to provide a device of this character which will hold the knot of a four-in-hand tie in shape and prevent loosening of the knot so that the tie will remain snugly attached to the collar at all times without attention.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

20 In the accompanying drawing forming part of this specification,

Figure 1 is a front elevation of a neck tie equipped with a tie holder constructed in accordance with the invention.

25 Figure 2 is a rear elevation of the neck tie partly tied and showing the slit tongue and prong of the holder engaged with a cross over portion of the knot to crimp said portion and prevent loosening of the knot.

30 Figure 3 is a front elevation of the neck tie holder.

Figure 4 is a rear elevation of the neck tie holder.

35 Figure 5 is a detail cross sectional view taken on the line 5—5 of Figure 4 showing the eccentric clamp.

Figure 6 is a detail cross sectional view taken on the line 6—6 of Figure 4 showing the tongue for crimping the cross over portion of the tie.

Figure 7 is a longitudinal sectional view of the neck tie holder taken on the line 7—7 of Figure 4.

Figure 8 is a rear elevation of a modified form of the invention showing a hinged spring clamp.

40 Figure 9 is a cross sectional view taken on the line 9—9 of Figure 8 with the clamp shown dotted in crossed position.

Referring now to the drawing in which like characters of reference designate similar parts in the various views, 10 designates a neck tie of the four-in-hand type having a knot 11 which as is customary is manually tied after the neck tie is applied to the shirt collar. In all knots a portion 12 thereof crosses inside of the knot from

one side to the other and may be called a cross over portion.

In carrying out the invention a neck tie holder 13 is provided formed of sheet metal and comprising a comparatively wide lower portion 14, best shown in Figures 3 and 4, which has its ends bent inwardly to provide flanges 15 for the reception of the end 16 of the tie, which is next adjacent the shirt when the neck tie is applied to the collar, as best shown in Figure 2. The flanges are 10 located at the rear side of the holder and are fully open at the upper and lower ends to permit the portion 16 to be slipped longitudinally of the holder between the flanges.

A cam clasp 17 is pivotally mounted on a transverse pivot pin 18 journaled at the ends in hinge ears 19 as best shown in Figures 4 and 7. The cam is provided with a depending hook 20 to facilitate opening and closing of the cam clasp and also to suspend an ornament therefrom if desired.

The upper portion of the clamp is extended to provide a tongue 21 which is provided with an elongated slit 22 having the upper end portion 23 reversed upon the body of the slit to provide a prong 24 which is offset from the tongue so that when the cross over portion 12 of the neck tie is passed over the tongue underneath the prong, as best shown in Figure 2, the cross over portion will be crimped so that it cannot shift in either direction and thus the knot is permanently held in shape and the neck tie cannot become loosened from the shirt collar.

In applying the device the inner end 16 of the neck tie is slipped between the side flanges 15 of the tie holder and the tie holder slid upwardly until the tongue 21 engages underneath the cross over portion 12 of the neck tie with the prong 24 engaged on the opposite side of the cross over portion in which position of the parts a transverse crimp will be formed in the cross over portion and also the lower edge of the cross over portion will be deformed upwardly as shown at 25 in Figure 2 so that the lower edge of the cross over portion is tightly gripped between the tongue and the prong and this deforming of the cross over portion coacts with the crimp in positively preventing any slipping of the cross over portion relatively to the tongue 23 and prong 24. 50 When the device has been applied as described the cam clasp 17 is rocked to closed position to bind the lower inner end portion 16 of the tie tightly against the wide body 14 of the clamp between the side flanges 15 thereof.

A hook 26 is secured to the rear side of the body of the clamp for securing an ornamental chain 27 which carries a tie clasp 28 of conventional character for binding together the front end portion 29 and the rear end portion 16 of the tie below the knot as best shown in Figure 1.

The tie clasp may be equipped with chains 30 at the ends which are trained over the front portion of the tie and are equipped with an ornament 31.

A modified form of the invention is shown in Figures 8 and 9 in which the body 32 of the clamp is comparatively wide and is provided with a tongue 33 having a longitudinal slot 34 provided 15 with a reversely extended portion 35 which forms a prong 36 for coacting with the tongue as above described. The prong is offset from the tongue by pressing out the material thereof as shown by full lines at 37. The body 32 of the holder is 20 provided on one side with hinge ears 38 through which a vertically disposed pivot pin 39 is passed to hingedly secure a clamp 40 to the holder. The free end of the clamp is provided with a reversely bent spring hook 41 which springs over an arcuate 25 flange 42 formed on the body 32, as shown by dotted lines in Figure 9 to hold the clamp closed. A plurality of lugs 43 is stamped from the clasp 40 to indent the rear end portion of the neck tie and prevent any tendency of the holder becoming dislodged from the neck tie.

From the above description it is thought that the construction and operation of the invention will be fully understood without further explanation.

35 What is claimed is:

1. A neck tie holder comprising a comparatively wide body provided at the ends with inturned flanges for the reception of the end of a neck tie which is next adjacent the shirt when the neck 40 tie is applied to the collar, said flanges being located at the rear side of the holder and fully open at the upper and lower ends to permit said portion of the neck tie to be slipped longitudinally of the holder between the flanges, means carried by 45 the flanges for clamping said portion of the neck tie to the holder, the upper portion of the holder being extended to provide a tongue having an

elongated slit, the upper portion of which slit is reversed upon the body of the tongue to provide a prong, said prong being offset from the plane of the tongue, said prong and tongue being adapted to straddle a cross over portion of the neck tie when the knot is tied and crimp and deform said portion so that said portion cannot shift in either direction. 5

2. A neck tie holder comprising a comparatively wide lower portion having its end bent inwardly to provide flanges which are open at the top and at the bottom to receive an end portion of a neck tie, a cam clasp pivotally mounted to rotate on a transverse pivot at the upper end of said flanges and bind said neck tie against said lower portion of the holder, the upper portion of the holder being extended to provide a tongue having an elongated slit reversed upon itself to provide a prong, the prong being offset from the tongue, the prong and tongue being adapted to 10 be placed astride a cross over portion of a neck tie to crimp and deform the cross over portion and prevent shifting of the cross over portion in either direction so that the neck tie knot is permanently held in shape and cannot become loosened from 15 the shirt collar. 20

3. A neck tie holder comprising a comparatively wide lower portion having its ends bent inwardly to provide flanges which are open at the top and at the bottom to receive an end portion of a neck tie, a clasp hinged to one of said flanges and having a curved free end adapted to spring over the other of said flanges, said clasp having a projection on the inner face adapted to indent the end portion of the neck tie and prevent any tendency 35 of the holder becoming dislodged from the neck tie, the upper portion of the holder being extended to provide a tongue having an elongated slit reversed upon itself to provide a prong, the prong being offset from the tongue, the prong and 40 tongue being adapted to be placed astride a cross over portion of a neck tie to crimp and deform the cross over portion and prevent shifting of the cross over portion in either direction so that the neck tie knot is permanently held in shape and 45 cannot become loosened from the shirt collar.

JOSEPH J. NUGENT.
